UNITED STATES PATENT OFFICE.

WILLIAM P. WALTER, OF ANGOLA, INDIANA.

INVALID-SUPPORT.

1,254,554.

Specification of Letters Patent. Patented Jan. 22, 1918.

Application filed February 16, 1916. Serial No. 78,725.

To all whom it may concern:

Be it known that I, WILLIAM P. WALTER, a citizen of the United States, residing at Angola, in the county of Steuben and State 5 of Indiana, have invented new and useful Improvements in Invalid-Supports, of which the following is a specification.

This invention comprehends the provision of an adjustable invalid support, primarily 10 designed for use in connection with a bed, and whereby the patient can be elevated with comfort above the bed, to permit of a change of bed clothes, or allow the back of the patient to cool with a view of preventing 15 bed sores, or for any other purpose.

In carrying out my invention I aim to provide a contrivance of the above mentioned character, which can be easily associated with a bed or removed therefrom when 20 desired, and one which can be easily elevated or lowered by the nurse or other person without any assistance.

The nature and advantages of the invention will be better understood from the following description, when read in connection 25 with the accompanying drawings, the invention residing in the construction, combination and arrangement of parts as fall within the scope of what is claimed.

In the drawings forming part of this 30 specification like numerals of reference indicate similar parts in the several views, and wherein:—

Figure 1 is a side elevation of my device 35 showing the same positioned with relation to a bedstead.

Fig. 2 is an end view.

Fig. 3 is a top plan view.

Fig. 4 is a longitudinal sectional view.

Fig. 5 is an enlarged detail view of the 40 connection between the component parts of the device.

Fig. 6 is an enlarged detail view of the rack and pinion for elevating the patient.

Fig. 7 is a horizontal sectional view 45 through one of the corner posts.

Fig. 8 is a detail view of the pawl and ratchet.

Before entering into a detail description 50 of what is herein shown and described, I desire to have it understood that the same is merely illustrative of one embodiment of the invention, and that such changes in the construction and arrangement of parts may be 55 resorted to when desired as fall within the scope of the claims.

Referring more particularly to the drawings the device forming the subject matter of my invention consists of a stationary frame A and a relatively movable frame B, 60 the latter being supported upon the stationary frame for vertical adjustment in the manner to be hereinafter described. The stationary frame A preferably consists of four corner posts 10 connected together by 65 means of upper and lower parallel side and end rails 11 and 12 respectively thereby providing a rigid construction. The frame when used in connection with a bed herein indicated at C, is arranged to straddle the 70 bedstead, the corner posts 10 being arranged beyond the opposite side rails of the bedstead and inwardly of the head and foot thereof, the frame in its entirety being supported upon the floor or surface. The end 75 rails 12 are preferably made in two sections to facilitate the association of the frame with the bed or its removal therefrom, and the adjacent ends of said sections are preferably formed with dove-tailed heads 13 80 adapted to be received within the sockets 14 of corresponding configuration.

The relatively movable frame B as shown in this instance consists of spaced parallel side rails 15 connected together through the 85 instrumentality of end rails 16. Journaled between the side rails 15 in close proximity to the end rails 16 at both ends of the frame are transverse shafts 17 which project through vertical slots 18 in the corner posts 90 10 of the frame A, the shafts 17 serving to support the frame B upon the frame A in a manner illustrated in Fig. 1, from which it will be noted that the movable frame B is adapted to be arranged above and normally 95 rest upon the mattress of the bed. Fixed upon the opposite extremities of the shaft 17 exteriorly of the corner posts 10 are pinions 19 adapted to mesh with the vertically disposed rack bars 20 secured to the 100 corner posts 10 at one side of the slots 18, by reason of which construction and arrangement it will be manifest that the frame B may be adjusted vertically upon rotation of the shaft 17. I preferably provide each 105 of the shafts 18 at the opposite ends of the frame B, with a suitable handle 21 by means of which the shafts may be rotated, it of course being understood that in elevating or lowering the frame B, one end is adjusted 110 a predetermined distance by rotating one of the shafts 17, and then the other end of the

frame is adjusted by rotating the other of the shafts 17. Secured upon the shafts 17 adjacent each end thereof are ratchet wheels 22 with which pawls 23 pivotally mounted upon the inner surface of the side rails 15 are adapted to coöperate, with a view of holding the opposite ends of the frame B in any adjusted position. In consideration of this fact it will be clear that a nurse or any other person may elevate or lower the frame B without any additional assistance, and that the frame in its entirety may be quickly and easily adjusted with the expenditure of a minimum amount of energy.

15 One of the end rails 16 of the frame B is stationary, while the other end rail is mounted for rotation, and projects a slight distance beyond one of the side rails 15 of the frame as at 24 to accommodate a suitable 20 rack or handle by means of which the end rail may be rotated. Fixed to the stationary end rail 16 is one end of a sheet of canvas or other suitable material indicated at 25, the opposite end of said material being secured to the rotary end rail and adapted 25 to be wound thereabout with a view of stretching the material taut across the bed. Fixed upon the rotary end rail 16 is a ratchet wheel 26 which is normally engaged 30 by means of a pawl 27 pivoted upon one of the side rails 15 of the frame and actuating to prevent retrograde movement of the rotary end rail, thereby holding the material taut when stretched. The contrivance in its 35 entirety may if desired form a part of the bed, or in other words remain associated therewith for an indefinite period of time, in which instance the canvas or material 25 would serve as a sheet for the bed upon 40 which the patient would rest. However when the contrivance is attached to the bed only when it is desired the canvas or material can be easily slipped beneath the patient and properly connected with the end 45 rails to be stretched prior to the adjustment of the movable frame B. It might be further stated that while the contrivance is shown used in connection with a single bed, the frames A and B can be made of a size 50 to accommodate a double bed without departing from the spirit of the invention, and that also the contrivance as a whole is susceptible for use wholly independent of the bed.

55 It is apparent that I have provided a device of the class in question by means of which a patient can be easily and quickly

elevated from the bed in comfort to permit of a change of bed clothing or for any other purpose, and by reason of the construction 60 and contemplated operation it will be further obvious that should the patient be suffering from hemorrhages the lower end of the frame B or that end adjacent the foot of the bed can be raised or elevated independently or without raising the opposite end of the frame.

What is claimed is:—

1. The combination with a bedstead, of an invalid support embodying a stationary frame, said frame including corner posts arranged in pairs at the opposite sides of the bedstead, parallel side and end rails connecting the corner posts, a movable frame arranged inwardly of the corner posts and supported thereon for vertical adjustment above the bedstead, said movable frame including spaced parallel side and end rails, said side rails being longitudinally slotted adjacent one end, transverse shafts carried 80 by the side rails of the movable frame and associated with the corner posts to permit said frame a vertical adjustment with respect to said posts, one of said shafts being arranged in said slots and a sheet of flexible 85 material carried by the end rails of the movable frame.

2. The combination with a bedstead, of an invalid support embodying a stationary frame, said frame including corner posts arranged in pairs at the opposite sides of the bedstead, side and end rails connecting the corner posts, said corner posts having vertically disposed slots, a second frame disposed above the bedstead inwardly of the 95 corner posts, said second frame including parallel side and end rails, said side rails having longitudinally disposed slots registering with the slots in the corner posts, transversely disposed shafts carried by the 100 second mentioned frame and having their extremities passed through the slots in the corner posts and said side rails, means for adjusting the movable frame vertically in the slots of the corner posts, and a sheet of 105 flexible material secured to the end rails of the movable frame.

In testimony whereof I affix my signature in presence of two witnesses.

WILLIAM P. WALTER.
